UNITED STATES PATENT OFFICE.

JAMES BLOUNT JORDAN, OF NASHVILLE, TENNESSEE.

SALIVA-EJECTOR.

SPECIFICATION forming part of Letters Patent No. 730,128, dated June 2, 1903.

Application filed June 9, 1902. Serial No. 110,885. (No model.)

To all whom it may concern:

Be it known that I, JAMES BLOUNT JORDAN, a citizen of the United States, residing at Nashville, in the county of Davidson and State of Tennessee, have invented new and useful Improvements in Saliva-Ejectors, of which the following is a specification.

This invention relates to a saliva-ejector for use in dental work; and the object of the invention is to provide an efficient device of this character which can be easily applied and which when in place is positively held in the mouth without discomfort to the patient or possible injury to the tender tissues of the mouth or gums and so that the operator can use both hands in working on the teeth and which carries off all saliva and water used during the work—for example, in grinding preparatory to putting on crowns. Other objects and advantages of the invention will be set forth in the following description, while the novelty thereof will constitute the basis of the claims succeeding such description, and said invention in one simple and convenient form thereof is clearly illustrated in the accompanying drawings, forming a part of this specification, and in which—

Figure 1 is a plan view of right-and-left saliva-ejectors arranged side by side and including my invention. Fig. 2 is a similar view of the left ejector with a holding-clip combined therewith. Fig. 3 is a detail perspective view of the same with the clip removed. Fig. 4 is a similar view of the clip. Fig. 5 is a cross-section through the extension of the device. Fig. 6 is a detail view in perspective of one of the wings.

Like characters refer to like parts in all the figures of the drawings. The improved instrument, which is of tubular form, includes a stem 2, provided at its upper end with a substantially U-shaped extension 3, and these parts may be made from any suitable material. The inner ends of the branches of said U-shaped extension 3 are preferably closed; but the lower end of the stem 2 is open. Such lower end of the stem is adapted to receive a tube of rubber or the like, which I have not deemed it necessary to show, as the same forms no part of the invention. At the lower end of this rubber tube a water suction-pump is generally ap-

plied, so as to draw the saliva and water from the patient's mouth through the ejector, one or both of the branches of the U-shaped extension of the ejector having an inlet for the entrance of such saliva or water. The upper end of the tubular stem 2 is bent at 4, so as to fit over the lip of the patient, and the major part of the length of the stem 2 extends in such direction from the U-shaped extension 3 that it will be aligned with the rubber tube before mentioned, so that the latter cannot exert any lateral stress upon the ejector, as in case it did it would tend to displace the same.

There are two of the ejectors shown, one for the left lower side of the mouth and the other for the right lower side. It will be understood, of course, that the stems 2 for the greater part of their length are so disposed that if the ejectors were in the mouth at the same time such stems would extend in parallelism, as shown by Fig. 1.

I will now describe in detail the ejector employed on the left. The branches of the U-shaped extension 3 are adapted to be contiguous to the lingual and buccal surfaces, respectively, of the lower gum, and the stem 2 is connected with the extension in proximity to the junction of said branches, and the extension and stem may or may not be in one piece, as desired. The rear portion of the extension 3 is deflected below the forward portion thereof, so that when such rear portion is in the mouth the front portion will extend above the tops of the teeth. The branches of the U-shaped extension are curved or arched to conform to the curvature of the gum against or near which they fit. The extension shown in Figs. 2, 3, and 5 is adapted to the left side of the mouth, and it will be evident that the curve of the branches of the other extension, or the one that is fitted in the right side of the mouth, is opposite to that shown in said figures. The inner or lingual branch of the extension 3 is somewhat shorter than its companion or buccal branch, so that it will not project into the throat. At or near the inner closed end of the inside branch of the extension 3 I form an inlet or perforation 5 for the entrance of saliva that collects under the tongue, and this inlet or perforation is open at all times. In the other

branch of the extension I provide a valved inlet hereinafter described, the valve of which is normally closed, so that the atmospheric air cannot normally enter such valved inlet 5 to oppose the ingress of saliva through the single inlet 5 in the inner branch. Also by providing a single inlet in the inner branch atmospheric air cannot enter the same when the valve in the other branch is closed. At 10 a point substantially midway of the outer branch of the extension 3 I form a circumferential channel 6, in which the band 7 is fitted for rotation, said band constituting a valve for the saliva-inlet 8 in said channel. 15 The valve or band 7 has a perforation 9 at a suitable point, which by turning said band or valve can be brought into registration with the inlet 8. The band or valve can be readily turned by a suitable instrument in the 20 hands of the dentist. It will be understood that normally the solid portion of the band or valve covers the perforation 9, so as to prevent the entrance of atmospheric air through such perforation. When the operator finds 25 it necessary to remove an accumulation of saliva from the outer surface of the gums, he simply opens the valve 7 while the instrument is in the patient's mouth, and when the saliva or any water that may have been used in 30 grinding work has been discharged the valve will be closed.

It will be understood that the saliva collects more quickly on the lingual surface of the mouth than on the buccal surface thereof, 35 by reason of which I provide a manually operable valve on the buccal drainage portion of the instrument, which valve is maintained normally closed, whereby atmospheric air cannot normally enter the valve-controlled inlet, 40 as in case it did it would pass into the buccal drainage portion and from the same into the communicating lingual drainage portion and oppose the entrance of saliva into the latter. When it becomes necessary to drain the buccal 45 surface of the mouth, the valve in question is opened by means of a suitable implement in the hands of the dentist, and when said valve is opened such drainage of the buccal surface can be quickly effected. As soon as 50 the buccal surface is drained of the saliva the valve is closed.

To the branches of the extension 3 I secure the wings 10, of highly-polished plate material. At least the inner surfaces of the plates 55 are highly polished, so that they can be used as reflectors or mirrors. The wings 10 are sleeved onto the branches of the extension, and to prevent said wings from turning I form upon said branches longitudinal keys or 60 ribs 11, which are adapted to fit in coöperating grooves in the bores of the sleeves 12, said sleeves being suitably formed at the opposite ends of the respective wings. Ordinarily the keys or ribs are made integral with the 65 respective branches of the extension 3; but of course this is not essential. A part of one

of the ribs is formed upon the turning valve or band 7. In certain kinds of dental work the wings are to be removed from their supporting branches, and it will be apparent that 70 they can readily be slipped from place and can be as easily put on; but before the outer wing can be removed it will be necessary to bring that part of the key 11 that is on the valve or band 7 into line with the coöperating 75 and relatively fixed sections of said key.

The tongue is adapted to come against the outer surface of the inner wing, and such outer surface is concaved to fit the tongue. This inner plate or wing, it will be evident, 80 prevents the tongue from coming in contact with the teeth upon which the dentist is working. The outer wing fits against the inside of the cheek, and its outer surface is convexed. Such outer plate of course prevents the cheek 85 from coming in contact with the teeth. The wings or plates, beside accomplishing the function of tongue and cheek depressors, also serve as guards, for in case the instrument that the dentist is using should slip the same 90 will strike one of said plates and be prevented thereby from injuring the patient.

I provide means for positively holding the ejector, or rather the extension 3 thereof, in the mouth, so that the same cannot be accidentally dislodged, and I will now set forth a simple device for securing this result. A clip is shown at 13, and its jaws are provided with concaved seats 14 to receive a tooth, so that the clip will be held firmly in position. The 100 said jaws are provided with spring-arms 15, which parts may be made integral and the spring-arms terminate in bends 16, adapted to yieldingly engage the branches of the extension 3. It will be evident, therefore, that 105 when the clip 13 is connected with a tooth and the bends 16 and in engagement with the branches of said extension the latter will be firmly held in place. By pressing the spring-arms 15 toward or from each other they can 110 be readily connected to or disconnected from the branches of the extension. It will be obvious that the clip, with its spring-arms, is reversible from back to front and can be interchangeably used with the two ejectors. 115

From the foregoing description it will be evident that my improved device comprises, broadly, buccal and lingual tubular drainage portions each having an inlet and one of the inlets being valved. 120

The invention is in nowise limited to the structure nor arrangement of parts hereinbefore set forth, for many variations as to these features may be adapted within the scope of the following claims. 125

Having described my invention, what I claim is—

1. A saliva-ejector having buccal and lingual tubular drainage portions, each having a saliva-inlet, and the inlet of the buccal portion having a manually-operable valve whereby said valve can be maintained normally 130

closed, and can be opened at intervals to permit the removal of accumulated liquid from the buccal surface of the mouth.

2. A saliva-ejector having buccal and lingual tubular drainage portions, each having a saliva-inlet, and a band rotative in a channel of the buccal drainage portion and constituting a valve and having a perforation adapted to register with the inlet in said buccal drainage portion.

3. A saliva-ejector having buccal and lingual drainage portions, each having a saliva-inlet, wings sleeved to said tubular drainage portions, a valve upon the buccal drainage portion for controlling the inlet thereto, and keys upon the tubular drainage portions to fit grooves in the sleeve of the respective wings, a part of one of the keys being formed upon said valve.

4. A saliva-ejector having buccal and lingual drainage portions, each having a saliva-inlet combined with a spring-clip connected with said drainage portions.

5. A saliva-ejector having buccal and lingual drainage portions, each having a saliva-inlet combined with a spring-clip connected

with said drainage portions, and having tooth-gripping jaws.

6. A saliva-ejector having a drainage part adapted to enter the mouth combined with 30 means for positively clamping such drainage part in the mouth against accidental dislodgment.

7. A saliva-ejector having buccal and lingual tubular drainage portions combined with 35 a spring-clip having arms for engaging said tubular drainage portions to hold the same against accidental dislodgment.

8. A saliva-ejector having buccal and lingual tubular drainage portions, and cheek 40 and tongue engaging wings carried by said drainage portions, the outer surface of the cheek-engaging wing being convexed and the outer surface of the tongue-engaging wing being concaved.

In testimony whereof I have hereunto set my hand in presence of two subscribing witnesses.

JAMES BLOUNT JORDAN.
